UNITED STATES PATENT OFFICE.

JOHN QUINCY REED, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,495, dated October 28, 1884.

Application filed August 7, 1884. Term of patent 3½ years.

To all whom it may concern:

Be it known that I, JOHN QUINCY REED, of the city, county, and State of New York, have invented and produced a new and original Design for a Pattern of a Lady's Costume, (numbered 9,356;) and I do hereby declare that the engraved prints accompanying this specification convey to any one accustomed to using paper patterns a clear understanding of how a garment made up by the pattern will appear.

The design shows a round walking-skirt and an overdress. The skirt exhibits a deep left-front drapery that displays draping plaits in its back edges, and a deep right-front drapery that exhibits draping plaits in its front and back edges, the draperies appearing to lap quite broadly at the top and flare widely in deep points nearly to the bottom of the skirt.

The overdress exhibits closely-fitted basque-fronts that outline a point at the end of the closing and curve over the hips, a closely-fitting basque-back, upon which appears to be draped a deep full back drapery that exhibits draping plaits at the center at the top, and deep loopings at the front edges, a standing collar, and coat-sleeves that display a gathering and a high roll at the shoulder.

What I claim as my invention, and desire to secure by Letters Patent, is—

The design for a lady's costume, as shown in the engraved prints accompanying this specification.

JOHN QUINCY REED.
